(57) **CLAIM**

The ornamental design for a vehicle rear spoiler, as shown and described.

DESCRIPTION

FIG. 1 is a top and left perspective view of a vehicle rear spoiler, showing our new design;

FIG. 2 is a bottom and left perspective view thereof;

FIG. 3 is a top rear perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines and the areas contained within illustrate portions of the vehicle rear spoiler that form no part of the claimed design.
